TISSUE HOLDER

Robert L. Hartley, Indianapolis, Ind., assignor to Harper J. Ransburg Co., Inc., Indianapolis, Ind., a corporation of Indiana

Filed Sept. 15, 1965, Ser. No. 87,012

Term of patent 14 years

(Cl. D52—2)

FIG. 1 is a front elevation of a tissue holder showing my new design.

FIG. 2 is an end elevation thereof;

FIG. 3 is a rear elevation thereof;

FIG. 4 is a plan view thereof; and

FIG. 5 is a vertical section taken on the line 5—5 of FIG. 4.

The end opposite the end shown in FIG. 2 has the same appearance shown in FIG. 2.

I claim:

The ornamental design for a tissue holder, as shown and described.
